UNITED STATES PATENT OFFICE.

CARL P. THOMPSON, OF TRION, GEORGIA.

BEAM-TRUCK.

1,261,974.

Specification of Letters Patent. Patented Apr. 9, 1918.

Application filed September 21, 1917. Serial No. 192,544.

To all whom it may concern:

Be it known that I, CARL P. THOMPSON, a citizen of the United States, residing at Trion, in the county of Chattooga and State 5 of Georgia, have invented certain new and useful Improvements in Beam - Trucks, of which the following is a specification.

This invention relates to certain new and useful improvements in trucks, and contem- 10 plates more especially an improved device for supporting and conveying yarn beams.

In the handling of yarn beams at the present time certain difficulties are experienced, in that the beam is carried on a truck 15 which receives the weight of the beam directly upon the yarn, thereby causing mutilation and crossing of the threads. The yarn is dented, marked and disarranged by this old method of transporting the beam, 20 which makes it extremely difficult to get a good lease of the yarn.

It is an object of the present invention to overcome these disadvantages, and produce an improved truck upon which the beam is 25 supported without denting, interfering with, or moving the yarn from its original position as it comes from the slashers.

Another object of this invention is the production of a truck, including in combination 30 relatively spaced supporting members having their surfaces longitudinally and transversely inclined, whereby the ends of the beam can be readily supported so that the yarn is kept substantially out of contact with the body of the truck.

A further object of the invention is to produce a balanced truck which can be easily handled and upon which beams of considerable weight can be easily supported.

40 The invention further consists in the combination and arrangement of the several parts and elements hereinafter described and pointed out in the appended claims.

In the accompanying drawing which 45 shows by way of illustration an embodiment of my invention,

Figure 1 is a side elevation of my improved truck, showing a yarn beam in dotted lines supported thereon.

50 Fig. 2 is a top plan view of the truck.

Fig. 3 is a detail cross sectional view on the line 3—3 of Fig. 2, and

55 Fig. 4 is a similar view to Fig. 3, illustrating a slightly modified form of the supporting members.

My improved truck has been primarily

designed for use in connection with the handling of yarn beams, but it will be understood that it can be utilized for the supporting and conveying of many other articles, the immediate contact of which with the truck body would be detrimental.

The truck comprises among other things a wheel supported and substantial flat body portion upon the upper side of which are 60 relatively located supporting members on which the ends of the beam rest. These supporting members are positioned at or near the four corners of the body portion of the truck, and are longitudinally and transversely inclined toward each other, as shown in the drawings.

Referring to the drawing in which corresponding reference characters designate similar parts, the truck body of my improved truck is of rectangular formation, supported at one end by suitably mounted wheels 2, and relatively elevated near the other end by means of rests 3 bolted to the under side of the said truck body. A suitable handle is also provided on the truck body and may be formed integral therewith as shown, or otherwise secured.

The beam supporting members are arranged on the body portion 1 in spaced pairs 85 5 and 6 at the wheel and handle ends of the truck, respectively.

The supporting members 5 include blocks 7 secured to the truck body 1 by bolts 8. These blocks 5 may be constructed of any 90 material such as wood, metal, or the like and are longitudinally inclined toward the intermediate portion of the truck, as shown in Fig. 1. They are also laterally beveled or inclined toward each other as shown in 95 Fig. 3. Upon the upper surface of these blocks are attached plates 9. These plates serve to receive the ends of the beam and protect the blocks against wear. Suitable screws 10 secure the plates 9 to the blocks. 100 It will be seen that the plates can be easily removed and new ones applied.

The supporting members 6, arranged at the opposite end of the truck, are similar in construction to the ones just described, 105 and include beveled or inclined blocks 11 secured to the truck body portion 1 by bolts 12. These blocks slant longitudinally toward the intermediate portion of the truck, (see Fig. 1), and are transversely beveled 110 or inclined toward each other as shown in Fig. 3. Suitable supporting and wear

plates 13 are secured to the blocks 11 by means of screws 14.

The opposite longitudinally and transversely inclined arrangement of these two pairs 5 and 6 of supporting members, serves to insure the staple positioning of the beam upon the truck, without locking and other attaching devices. The relative location of these supporting members to each other and 10 to the truck body serves to effect a substantially self balancing truck upon which loads of large and varying weights can be supported. Different length beams can also be accommodated without affecting the easy 15 handling of the truck.

A cross bar 15 is provided at the wheel end of the truck to prevent the beam from slipping off when the truck is elevated to a high degree.

20 In practice the yarn beam is placed upon the truck with one end upon the supporting members 5 and the opposite end upon the supporting members 6. The end of the beam upon the supporting members 5 is placed in close proximity to the cross bar 15. The handle 4 is then gripped and the truck is elevated sufficiently to conveniently transport the beam. It will be seen that the resting of the two ends of the beam upon the 25 respective supporting members, acts to keep the yarn substantially out of contact with the truck. It will also be apparent that should the extreme ends of the yarn contact with the supporting members, the inclined 30 arrangement of the plates will serve to uniformly support the yarn in an undisturbed position, and in no instance dent, mark, or cross the yarn.

The modified construction shown in Fig. 40 4 of the drawings comprises a single block 16 cast, machined or otherwise formed of a substantially hard and wear-resisting material. This form of block is readily attached to the body portion 1 of the truck

by means of through bolts 17 counter-sunk 45 as shown.

From the foregoing it is obvious that I have produced a simple, cheaply manufactured, and highly advantageous design of truck, capable of supporting a yarn beam 50 with the weight thereof relatively distributed, and with the yarn out of damaging contact with the truck body.

What I claim is:—

1. A beam truck of the class described including in combination a wheeled truck body and a plurality of spaced and elevated beam supporting members each of said members having their upper faces inclined longitudinally and transversely toward each other and adapted to receive a minimum portion of the contacting surfaces of the load supported. 55

2. A beam truck of the class described including in combination a wheeled truck body, a rest for said truck, oppositely arranged beam supporting members provided on said truck body having inwardly extending inclined upper surfaces adapted to receive a minimum portion of the contacting 60 surfaces of the load supported, and a cross bar connecting two of said members. 65

3. A beam truck of the class described including in combination, a wheeled truck body, and a supporting member arranged at 70 each corner of said truck body, each of said supporting members having a transversely and longitudinally inclined upper surface adapted to receive a minimum portion of the contacting surfaces of the load supported. 75

In testimony whereof I affix my signature in the presence of two witnesses.

CARL P. THOMPSON.
